BULB HOLDER

George E. Trust, Plainfield, N. J.

Application April 29, 1933, Serial No. 668,635

4 Claims. (Cl. 173—356)

This invention relates to means for conveniently carrying replacement bulbs for use on automobiles and consists in the provision of a device provided with a plurality of lamp sockets 5 for accommodating the bulbs, together with means for efficiently locking the bulbs in the sockets against unauthorized removal.

The invention, together with its numerous objects and advantages, will be best understood 10 from a study of the following description, taken in connection with the accompanying drawings, wherein:

Figure 1 is a side elevational view of the device, the same being shown conveniently mounted 15 on the dash board of an automobile.

Figure 2 is a front elevational view of the device.

Figure 3 is a rear elevational view thereof.

Figure 4 is a vertical sectional view taken substantially on the line 4—4 of Figure 3.

Figure 5 is a fragmentary detail view taken substantially on the line 5—5 of Figure 4.

Figure 6 is a fragmentary sectional view on an enlarged scale and taken substantially on the line 6—6 of Figure 5.

Figure 7 is a perspective view showing the manner of locking the bulb within its socket.

Figure 8 is a sectional view taken substantially on the line 8—8 of Figure 7.

Referring to the drawings by reference numerals, it will be seen that the device comprises a panel 10 of metal or other suitable material provided with a marginal flange 11, and in the present instance, the panel 10 is integral with 30 a suitable housing 12 in which is suitably mounted a drum 13. On the drum 13 is windable the cord 14 of a trouble light 15, the cord 14 operating in a longitudinal slot 16 provided therefor in the front of the housing 12 as shown.

In this connection, it will also be noted that, provided on one end of the drum 13, is a conductor ring 17 insulated from the drum as at 18. Wiping against the ring 17 is a spring contact 19 suitably mounted on the flange 11 and insulated therefrom as at 20. One end of the electric cord 14 is connected with the ring 17 in any suitable manner for supplying current to the lamp 15 from any suitable source of supply, preferably from the lighting system of the automobile.

Suitably mounted on the panel 10 are a plurality of lamp sockets 21 certain of which, as clearly shown in Figure 6, are provided with double contacts for accommodating automobile headlight bulbs, while other of the sockets are

adapted to receive, for example, cowl, tail or signal light bulbs.

Each of the sockets in the present instance is provided with one or more bayonet slots 22 for accommodating the pin or pins 23 with which the pins of the lamp bulbs 24 are usually provided for retaining the bulbs within the sockets.

On the rear side of the panel 10 there is provided a locking plate 25 that is slidably secured to the panel through the medium of bolt and slot means 26 as shown in Figure 5. Also mounted on the rear side of the panel is a key controlled lock 27 the bolt 28 of which is secured to a portion of the plate 25 in any suitable manner as by being integral therewith, soldered thereto, or as may be otherwise found desirable.

The plate 25, in the present instance, is provided with enlarged openings 29 to accommodate the inner ends of two of the sockets 21. The plate 25 in proximity to each of the sockets 21 is provided with a pinlike projection 30 to engage in the bayonet slots 22 of an adjacent lamp socket behind the pin 23 of the lamp bulb mounted in the socket in a manner clear from a study of Figures 7 and 8 thereby positively securing the lamp bulb in its socket against unauthorized removal when the lock actuated plate 25 is secured in locked position, which is the position shown in Figure 5.

It will thus be seen that the panel 10 will accommodate a plurality of lamp bulbs and that the bulbs may be securely locked within the lamp sockets against unauthorized removal.

Means is also provided for testing the bulbs 24 and in this connection there is provided at 90 the inner side of the panel 10 a block 31 of insulating material and a plurality of spring contact fingers 32 are suitably secured to the block. As shown in Figure 3, the contact fingers are electrically connected with the contacts of the 95 lamp sockets through the medium of wires 33. In this connection it also will be noted that one of the contacts 32 is connected with the contact 19 through the medium of a wire 34 while a second one of the contact fingers 32 has electrically 100 connected thereto one end of a lead wire 35 for supplying current to the bulbs from the wiring system of the automobile.

Suitably journaled at the rear side of the panel 10 is a roller 36 provided at one end with a 105 handle 37 to facilitate turning of the roller. The roller 36 comprises a cylindrical body of insulating material to which is suitably secured a substantially sleeve-like member 38 of conductive material, the member 38 having portions slotted 110

and removed for exposing, in the path of the contact fingers 32, portions of the insulation body 36 of the roller as the roller is revolved for making contacts between the sleeve 38 and the device 5 sired one of the spring fingers 32 to test a selected bulb 24.

While of course the device may be mounted on any suitable support within the automobile it has been preferable to mount the same on the 10 dashboard 39 of the automobile beneath the hood 40 as shown in Figure 1, and when so mounted it will be noted that the only parts of the device which are accessible are the bulbs and the key-hole of the lock 27, the dash board 39 closing 15 the open and rear side of the device as is apparent.

The use of the device is thought to be clear from the foregoing description, it being obvious that whenever desired the trouble light can be 20 readily pulled to unwind its cord 14 to bring the light 15 into proximity to the part being repaired; while when it is desired to remove one of the bulbs 24, the particular bulb may first be tested by properly manipulating the handle 37 25 to rotate the roller 36 for closing the circuit to the selected bulb. To remove the bulb from its socket, the lock 27 is operated for shifting the plate 25 to withdraw a pin 30 associated with the plate from the bayonet slot of the socket thus 30 permitting the bulb 24 to be rotated relative to its socket and subsequently withdrawn therefrom.

It will be seen from the foregoing that a simple yet thoroughly practical and efficient device 35 is provided for carrying replacement bulbs for use on automobiles and for so locking the bulbs as to prevent unauthorized removal thereof.

What is claimed is:

1. A holder for automobile light bulbs comprising a panel provided with a plurality of lamp sockets having slots in the walls thereof for receiving the stems of bulbs of the type provided with lateral retaining pins, a locking plate slidably mounted on the panel and provided with 40 projections arranged to engage in the bayonet slots behind the pins of the lamp bulb stems for locking the bulbs against rotation in the sockets, and a key controlled lock device mounted on the 45

panel engaged with said plate for shifting it and for securing it in position.

2. A device of the class described comprising a panel provided with a lamp bulb socket, having the common bayonet slots for receiving the 80 common lateral pins of the bulb stem for retaining the bulb in the socket when the bulb stem is inserted in the socket and turned to move the pins into engagement with the bayonet slots, and a key controlled locking device mounted on 85 the panel and including a member shiftable relative to the panel and having a projection adapted to enter a bayonet slot to engage there-in behind the pin of the bulb stem after the bulb stem has been turned to move the pin into final 90 retaining position within the bayonet slot of the socket to thereby secure the bulb within the socket against unauthorized removal.

3. In a device of the character described, a support, a plurality of lamp sockets mounted 95 on the support and each provided with the common bayonet slot for receiving the common lateral pin of bulb stem, a key controlled lock mounted on the support and including a bolt, a locking plate slidably mounted on the support 100 connected with the bolt to shift therewith, and provided with openings through which the sockets extend and a projection on the plate at the edge of each opening to enter a bayonet slot to 105 secure the pin of a bulb stem within said slot.

4. In a device of the character described, a panel, a plurality of lamp sockets mounted on the panel and provided with the common bayonet slots for receiving the common lateral pins on the stems of lamp bulbs for retaining the 110 bulbs in the sockets against casual displacement, a plate shiftably mounted on the panel and provided with apertures for accommodating certain of the lamp sockets, projections on the plate at the edge of the openings for projecting into 115 bayonet slots provided in the sockets accommodated by said openings to prevent removal of the bulbs, additional projections on the edge portion of the plate to project into bayonet slots in other of the sockets, a key controlled lock, 120 and an operating connection between the bolt of the lock and said plate for shifting the latter into and out of locking position.
